FIG. 5

A cross-sectional diagram of a structure, likely a door or window frame, divided into four vertical sections by dashed lines. The parts are labeled as follows:

- Top section: 53 (top), 19 (top right).
- Left section: 63 (top), 55 (middle), 74 (bottom).
- Middle section: 59 (top), 56 (bottom).
- Right section: 57 (top), 58 (middle), 75 (bottom).
- Bottom section: 61 (left), 54 (left), 62 (right), 52 (right).

FIG. 2

FIG. 1

FIG. 4 shows a rectangular frame with internal components. The frame is bounded by dashed lines. Internal components include a horizontal bar at the top labeled 36, a central vertical column with horizontal lines labeled 23 and 51, and a bottom horizontal bar labeled 28. External components include a vertical bar on the right labeled 17, a vertical bar on the right labeled 27, a vertical bar on the right labeled 33, a vertical bar on the bottom right labeled 21, a vertical bar on the bottom left labeled 29, a vertical bar on the left labeled 32, a diagonal line labeled 24, a diagonal line labeled 34, a vertical line labeled 25, a vertical line labeled 30, a vertical line labeled 35, a vertical line labeled 26, and a vertical line labeled 22.

OUTBOARD MOTOR PACKAGE

Paul F. Boeye, Mound, and Harry F. Collins, Jr., Minneapolis, Minn., assignors to Northwestern Corrugated Box Co., Minneapolis, Minn., a corporation of Minnesota

Application November 17, 1955, Serial No. 547,387

4 Claims. (Cl. 206—45.14)

The herein disclosed invention relates to packages for carrying outboard motors and has for an object to provide a package whereby the motor will be protected from injury during shipment and storage.

Another object of the invention resides in providing a container having an insert therein and on which the motor is mounted.

A still further object of the invention resides in constructing the insert with a front section, a rear section and an upper section, and in providing a crossbar supported by one of the sections and to which the clamps of the motor may be attached.

An object of the invention resides in constructing the front and rear sections with overlying transverse walls and to one of which the crossbar is attached and in providing flanges issuing from the lateral edges of the transverse walls and adapted to lie along the side walls of the container and extending substantially up to the front and rear walls thereof.

Another object of the invention resides in constructing the first and second sections so that they rest on the bottom wall of the container and of a height less than the height of the container to leave a space above the same and in attaching the crossbar to the upper end of the transverse wall of one of said sections to bring the motor proper into said space.

A still further object of the invention resides in utilizing the third section to hold the first two sections in place.

An object of the invention resides in constructing the sections so that the same may be assembled to form a display for the motor when removed from the container.

Other objects of the invention reside in the novel combination and arrangement of parts and in the details of construction hereinafter illustrated and/or described.

In the drawings:

Fig. 1 is a plan-sectional view of a container and insert illustrating an embodiment of the invention and taken on line 1—1 of Fig. 2.

Fig. 2 is an elevational-sectional view taken on line 2—2 of Fig. 1.

Fig. 3 is an elevational-sectional view taken on line 3—3 of Fig. 1.

Fig. 4 is a developed view of the blank from which the front section of the insert is constructed.

Fig. 5 is a developed view of the blank from which the rear section of the insert is constructed.

Fig. 6 is a developed view of the blank from which the top section of the insert is constructed.

Fig. 7 is a perspective view showing the insert assembled as a display and supporting the motor.

Fig. 8 is a plan view of the structure shown in Fig. 7 with the motor removed.

The invention may be used with an ordinary container or carton constructed of corrugated paper board and indicated in its entirety by the reference numeral 10. This container has a front wall 11, a rear wall 12 and side walls 13 and 14, being open at the top and bottom. Flaps 15 issuing from the upper ends of the lateral walls

2

of the container are adapted to be secured together to form a top 20 for the container and other flaps 38 issuing from the lower ends of these walls may be secured together to form a bottom 39 for the container.

5 Within the container 10 is mounted an insert 16 also constructed of corrugated board. This insert is formed in three sections and has a front section 17, a rear section 18 and a top section 19. These sections are arranged as shown in Fig. 3 and closely fit within the 10 walls of the container 10.

The front section 17 is constructed from a blank 21 shown in detail in Fig. 4. This blank is of a height less than the height of the container 10 and is rectangular in form. Extending from the lower edge 22 to the upper 15 edge 23 of said blank are vertically extending scores 24, 25, 26 and 27. These scores divide the blank into a transverse wall 28, side walls 29 and 30 and flaps 32 and 33 issuing from the outer edges of the walls 29 and 30. In addition, the walls 29 and 30 are formed with diagonal 20 scores 34 and 35 which form in the blank wings 36 and 37 which may be bent outwardly therefrom for a purpose to be presently described. The blank 21 when folded is U-shaped in cross section and the side walls 29 and 30 lie along the side walls 13 and 14 of the container 10 while the flaps 32 and 33 lie along the front wall 11 of said container. The lower edges 22 of the section 25 rest upon the bottom wall 39 of the container and the upper edge 23 thereof falls short of the top 20 of the container while the transverse wall 28 is disposed inwardly 30 of the rear wall 12 of the container.

The rear section 18 is constructed from a blank 40 shown in Fig. 5 and is of the same height as the section 17.

Extending from the lower edge 41 of this blank to the upper edge 42 thereof are two scores 43 and 44. These 35 scores divide the blank into a transverse wall 45 and side walls 46 and 47. When the blank is folded U-shaped in form and inserted into the container 10 the transverse wall 45 butts up against the transverse wall 28 of the section 17 while the side walls 46 and 47 lie along the

40 side walls 13 and 14 of the container 10. The vertical edges 48 and 49 of the side walls 46 and 47 butt up

45 against the rear wall 12 of the container. The edge 41 of this section rests upon the bottom 38 of the container. The transverse walls 28 and 45 are preferably fastened

45 together by gluing or otherwise so that the sections 17 and 18 are inserted as a unit.

Attached to the transverse wall 28 of the section 17 is a cleat 51 which is constructed of wood. This cleat 50 may be glued to the transverse wall 28 or the same may be secured thereto in any other manner.

The top section 19 of the insert is constructed from a blank 52 shown in Fig. 6. This blank is of a width between its lateral edges 53 and 54 equal to the depth 55 of the container between the front wall 11 and the rear wall 12. The said blank is formed with transverse

55 scores 55, 56, 57 and 58 which divide the blank into a top wall 59, side walls 61 and 62 and flaps 63 and 64, issuing from the lower edges of said side walls 61 and 62. The side walls 61 and 62 of the blank 52 are formed

60 with slots 74 and 75 which extend inwardly from the edge 53 thereof and lie parallel to the scores 56 and 57, being spaced a short distance therefrom. When the section 19 is folded and inserted into the container, the same fills the space 73 above the sections 17 and 18.

65 In such position, the top wall 59 overlies the top 15 of the container, the side walls 61 and 62 lie along the sides 13 and 14 of the container, while the flaps 63 and 64 rest upon the upper edges 23 and 42 of the sections 17 and 18.

70 For the purpose of illustrating the application of the invention, an outboard motor 65 has been shown, which is constructed with a motor proper disposed within a

motor case 66. A substructure 67 depends from the motor case 66 and carries the propeller 68 and the driving mechanism therefor. Mounted forwardly on the substructure 67 are clamps 69 and by means of which the motor may be secured to the transom of the boat with which it is to be used.

The method of packaging the motor is as follows: The container 10 is first erected and the lower flaps 38 thereof brought into overlying position and secured together to form the bottom 39 of the container. The sections 17 and 18 of the insert are next inserted into the container as shown in Fig. 1 with the side walls of said sections lying adjacent the side walls of the container. This construction forms a space 71 within the section 17, a space 72 within the section 18, and a space 73 above both of the sections. The substructure of the motor is next inserted into the space 71 and the clamp 69 mounted on and attached to the crossbar 51. Tethering means, not shown, is applied between the lowermost portion of the substructure 67 of the motor and the transverse walls 28 and 45 of sections 17 and 18 to assist in holding the motor in position. The motor case 66 then becomes disposed within the space 73. The top section 19 is now folded and inserted into the space 73 to cause the side walls 61 and 62 thereof to lie adjacent the side walls 13 and 14 of the container 10 and with the flaps 63 and 64 resting upon the upper edges 23 and 42 of the sections 17 and 18. The height of the side walls 61 and 62 of the section 19 is such that when the section is in position the top wall 52 lies directly beneath and substantially in contact with the top 39 of the container. The flaps 15 of the container may now be folded over and secured together to form the top 20 of the container. The outboard motor is now rigidly housed within the container and packaged for handling and shipping.

The insert of the invention is so constructed that when removed from the container the same may be erected to form a display for the outboard motor as shown in Figs. 7 and 8. For the purpose, the sections 17 and 18 are erected as shown in Fig. 8 and caused to rest upon the lower edges 22 and 41 thereof. The walls 46 and 47 of the section 18 are bent outwardly and rearwardly at an angle, as shown, while the side walls 29 and 30 of the front section 17 are brought together in substantial alignment with the walls 46 and 47. The wings 36 and 37 are now swung outwardly as shown in both Fig. 7 and Fig. 8. The top section 19 is next folded as shown in Fig. 8 and the same applied to the rear section 18 by inserting the uppermost portions of the side walls 46 and 47 of said section into the slots 73. Display matter may be applied to the surfaces of the walls 59, 61 and 62 of the section 19 and to the wings 36 and 37 of section 17. It will be noted that the section 19 is disposed rearwardly of and spaced from the transverse walls 28 and 45 of the sections 17 and 18 leaving the upper edges 22 and 41 of the sections 17 and 18 exposed. The motor may now be placed upon the display by causing the portions of the case 66 to rest on the edges 23 and 42 of the sections 17 and 18 and with the substructure 67 of the motor to rest upon the portions of the wings 36 and 37 at the scores 34 and 35. The motor is thus adequately supported and in an inclined position so that observers passing by the display may see the entire motor without stooping.

The advantages of the invention are manifest. The package is extremely simple and can be constructed at a nominal cost. The motor is held supported away from the walls of the container in which the insert is mounted so that injury thereto is prevented. The insert need not be destroyed and can be maintained in the container for storing the motor when the same is not in use. When the insert is erected, a display is provided in which the motor is supported in an inclined position affording the observer full view without stooping. Additionally, sufficient space is provided on the surfaces of the insert on which advertising matter can be placed.

Changes in the specific form of the invention, as herein described, may be made within the scope of what is claimed without departing from the spirit of the invention.

Having described the invention, what is claimed as new and desired to be protected by Letters Patent is:

1. In a package for carrying an outboard motor and including a container having a top, a bottom, a front wall, a rear wall and side walls, the combination of an insert comprising a front section having a transverse wall extending from one side wall to the other of said container, side walls issuing from said transverse wall and lying along the side walls of the container and extending substantially up to the front wall thereof, diagonal scores on the side walls of said first section running from the upper portions of the same near the transverse wall thereof and to the lower portions of the same near the front edges thereof and forming wings adapted to extend outwardly from the lower and rear portions of said side walls and on which display matter may be placed so as to be visible when the section is removed from the container and caused to rest on its lower edges and wings folded back, a rear section having a transverse wall overlying the transverse wall of the front section, side walls issuing from the transverse wall of the rear section lying along the side walls of the container and extending substantially up to the rear wall thereof, said sections resting on the bottom of the container and falling short of the top thereof to leave a space therebetween, a cross bar attached to one of said transverse walls at the upper end of the same and to which the clamps of an outboard motor may be attached to bring the motor proper in said space and means disposed within said space and engageable with the upper ends of said first and second sections and with the top of the container for holding said first and second sections in position within the container.

2. In a package for carrying an outboard motor and including a container having a top, a bottom, a front wall, a rear wall and side walls, the combination of an insert comprising a front section having a transverse wall extending from one side wall to the other of said container, side walls issuing from said transverse wall and lying along the side walls of the container and extending substantially up to the front wall thereof, diagonal scores on the side walls of said first section running from the upper portions of the same near the transverse wall thereof and to the lower portions of the same near the front edges thereof and forming wings adapted to extend outwardly from the lower and rear portions of said side walls and on which display matter may be placed so as to be visible when the section is removed from the container and caused to rest on its lower edges and the wings folded back, a rear section having a transverse wall overlying the transverse wall of the front section, side walls issuing from the transverse wall of the rear section lying along the side walls of the container and extending substantially up to the rear wall thereof, said sections resting on the bottom of the container and falling short of the upper wall thereof to leave a space therebetween, a crossbar attached to one of said transverse walls at the upper end of the same and to which the clamps of an outboard motor may be attached to bring the motor proper in said space, and a third section disposed within said space and having a top wall adapted to extend along the top wall of said container and side walls issuing from said top wall and adapted to extend along the side walls of said container and downwardly substantially to the upper ends of the side walls of said first and second sections to hold the same in position, said side walls of the third section having slots in the front edges thereof adapted to receive the upper portions of the side walls of the second section when the insert is removed from the container and to support said third section above the other sections with the top wall thereof parallel to the transverse walls of said first and second sections.

3. A display for an outboard motor comprising a front section and a rear section having overlying vertical transverse walls secured together, side walls issuing from the vertical edges of said transverse walls, the side walls of said first section being adapted to extend toward each other in converging relation and the side walls of said second section being adapted to extend away from each other in diverging relation, diagonal scores on the side walls of said first section running from the upper portions of the same near the transverse wall thereof and to the lower portions of the same near the front edges thereof and forming wings adapted to extend outwardly from the lower and rear portions of said side walls in coplanar relation at the foremost portion of the display and on which display matter may be placed.

4. A display for an outboard motor having a motor case and a substructure, said display comprising a front section and a rear section having overlying vertical transverse walls secured together the upper edges of said transverse walls forming a support for engagement with the motor case, side walls issuing from the vertical edges of said transverse walls, the side walls of said first section being adapted to extend toward each other in converging relation and providing a compartment for the reception of said substructure, and the side walls of said

5

10

15

25

second section being adapted to extend away from each other in diverging relation, diagonal scores on the side walls of said first section running from the upper portions of the same near the transverse wall thereof and to the lower portions of the same near the front edges thereof and forming wings adjacent the substructure adapted to extend outwardly from the lower and rear portions of said side walls and on which display matter may be placed, and a third section having a rear wall and side walls issuing from opposite ends thereof, said side walls having slots therein adapted to receive the uppermost portions of the side walls of said second section to position said rear wall in spaced parallel relation to said transverse walls to form a compartment receiving the motor case.
